UNITED STATES PATENT OFFICE

HENRY C. SMITH, OF CLEVELAND, OHIO, ASSIGNOR TO JOSEPH D. BENNETT,
HENRY S. BISHOP, AND BENJAMIN FAWCETT.

IMPROVEMENT IN IRONING-TABLES.

Specification forming part of Letters Patent No. **147,802**, dated February 24, 1874; application filed November 11, 1873.

To all whom it may concern:

Be it known that I, HENRY C. SMITH, of Cleveland, county of Cuyahoga and State of Ohio, have invented a new Improvement in Ironing-Tables, of which the following is a specification:

This improvement relates to a device for latching or bolting the supporting-legs to the under side of the table at the center, whereby the supporting-legs may be secured, enabling the table to be lifted or moved about without the said supports becoming disarranged. The said latching device is so arranged that the table may be adjusted to different heights, so that the table may be used for a sewing-table, it being convenient, when set at the lower point, to the lap of a person while sitting in a chair, for cutting out work as on a lap-board, and is also adjustable, as an ironing-table, for tall or short persons.

In the accompanying drawing, Figure 1 is a perspective view of an ironing-table having my improvement attached. Fig. 2 is a view of the table folded.

A is the table-top. B B are long supporting-legs, hinged at the head of the table. C C are short supporting-legs, pivoted, at *a*, to the legs B B. On the under side of the table A is a cleat, D, placed lengthwise, and having a series of holes, *d d*, through it. The upper cross-piece *c* of the legs C C has a slot cut in it, which embraces the cleat D, and to which is secured a sliding bolt, E, by means of which the supports C C are latched or fastened to the top A, the said holes *d d* enabling the legs C C to be secured at different points, so that the table may be adjusted at various heights.

What I claim is—

The combination, with an ironing-table, substantially such as herein described, of the slotted cross-piece *c*, perforated cleat D, and bolt E, for adjusting and securing said table at various heights, as specified.

H. C. SMITH.
